UNITED STATES PATENT OFFICE.

ENRIQUE JIMÉNEZ NÚÑEZ, OF GUADALUPE, SAN JOSE, COSTA RICA.

HOMEOPATHIC SHEET REPERTORY.

Application filed July 13, 1922. Serial No. 574,644.

To all whom it may concern:

Be it known that I, ENRIQUE JIMÉNEZ NÚÑEZ, a citizen of Costa Rica, residing at Guadalupe, Provincia de San José, Costa Rica, Central America, have invented certain new and useful Improvements in Homeopathic Sheet Repertories, of which the following is a specification.

This invention relates to the art of practicing medicine, and the primary object of the invention is to provide means for aiding in the selection of remedies for the proper treatment of diseases of the body.

A treatise by Allan Boenninghausen has been placed upon the market in book form, giving lists of different medicines for the treatment of diseases, the medicines for the treatment of each symptom of a disease being written in different characters to show the relative value of each medicine for the treatment of each symptom of a disease. While this treatise is an aid to practicing homeopathic physicians, the time required to look up the necessary remedies for the symptoms of different diseases has prohibited the general adoption of the book by the homeopathic profession.

Therefore, another object of the invention is to provide a repertory so formed and arranged as to permit the easy and rapid scrutiny of all known remedies of different symptoms of different diseases so as to effectively aid a physician in the correct selection of medicines for the treatment of the disease or diseases disclosed by his diagnosis of the patient.

A further object of the invention is the provision of a card system for aiding in the selection of remedies for the treatment of different diseases embodying a plurality of cards, each card representing a symptom of a disease, and divided into a plurality of independent spaces or blocks consecutively numbered, each number representing a certain medicine known in the art, the medicine or medicines which act for remedies for the symptoms being marked on the spaces or squares in a distinctive manner, such as by perforating the said spaces or squares, so that to see the medicines necessary to the treatment of certain symptoms of a disease, it is merely necessary to select the desired card and see which spaces are perforated. As certain medicine may have greater values for treating the symptoms of the disease than others, the spaces per-

forated are marked with different colors, each color representing the valuation of the medicine, for the treatment of the symptom.

A further object of the invention is to provide a novel means for arranging the cards in numerical order, so that the same can be readily selected, a novel means for arranging all of the names of the medicines in a book, and a number written beside the same corresponding to the numbers placed in the spaces or squares on the cards.

A further object of the invention is to provide novel means for quickly determining the medicine or medicines necessary for a patient having a number of different symptoms, it merely being necessary to select the cards bearing the symptoms and disposing the cards in superposed relation, and the perforated spaces which align indicating the medicine or medicines to be prescribed.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a perspective view of a number of the cards which have been selected as a result of a diagnosis of a case.

Figure 2 is a plan view showing the cards disposed in superposed relation to permit the finding of the necessary medicine or medicines for the treatment of the patient.

Figure 3 is a plan view of one of the sheets or cards.

Figure 4 is a fragmentary elevation of one leaf of a book which can be used as an aid in the selection of the cards or sheets.

Figure 5 is a fragmentary elevation of another leaf of the book or sheet showing the method of arranging the names of the medicines on the leaf or sheet to aid the physician in the finding of the names of the medicines found by superposing the cards.

Figure 6 is a fragmentary enlarged view showing a corner of one of the cards with details thereof.

Referring to the drawings in detail, where in similar reference characters designate corresponding parts throughout the several views, the letter A represents the improved repertory; and B and C, leaves or sheets from a book for co-operation with said repertory.

The repertory A includes a plurality of

sheets or cards 10 of substantially the same size and configuration. Each one of these sheets represents a different symptom of a different disease. The upper portion of each card or sheet is preferably provided with transverse lines 11 upon which the symptom indicated by the reference character 12 is adapted to be written or printed. These cards or sheets 10 are preferably numbered consecutively, and the card at each upper corner thereof is provided with a number indicated by the reference character 13.

Now, the main body portion of each card is divided by longitudinal and transverse lines 14 and 15 into a plurality of equal spaces or blocks 16.

These blocks or spaces 16 are formed to represent all of the known remedies for treating various symptoms, and each block 16 has a number indicated by the reference character 17 printed or written therein to indicate a certain medicine. These numbers 17 correspond to the numbers 18 written in front of the names of the medicine indicated by the reference character 19 on the leaves or sheets C, and thus it can be seen that to find the name of a medicine indicated by a certain number, for example the number 327, it is merely necessary to look on the leaf bearing the number 327 and the name "Plantago" will be found, thus indicating that that is the medicine represented by the number 327.

Now, it is also preferred to have the numbers of the cards 10 arranged in consecutive order on the sheets or leaves B as indicated by the reference character 20 and the names of the symptoms represented by said numbers are printed or written opposite to said numbers as indicated by the reference character 21 and clearly shown in Figure 1 of the drawings, and thus when it is desired to find the number of a certain card representing a certain symptom after the diagnosis of a case, it is merely necessary to look on the leaves B to find the required number, thus, say the physician desired to find the card representing constipation on account of hard faeces, it would be merely necessary to look on the leaves B and find the number of the card 492, after which he could withdraw the card from the pack of cards.

Now, the medicines which would act for a remedy as the symptoms listed on the cards or sheets 10 are struck out as indicated by the reference character 21. Thus, each sheet will have a number of perforations therein.

It is evident that some medicines are better than others for treating the symptom indicated on the card, and in order to show the physician which are the best remedies, the blocks which are perforated are marked in a distinctive manner. Thus, the medicines which are considered best for treating the symptoms shown are colored black, as

indicated by the reference character 22. The medicines considered next best are colored red, as indicated by the reference character 23. The medicines considered next best are colored blue, as indicated by the reference character 24. The medicines considered next best are left blank or white, while the medicines which are considered still less valuable are colored green as indicated by the reference character 25. Thus, the physician prescribing the medicine for the patient would select the medicine indicated by the black or red colorations preferably.

Now, in use, the card sheets 10 constituting the repertory are arranged in numerical order and can be arranged in groups running from 1 to 200, from 200 to 400, and so on, so that individual cards can be readily selected therefrom, and these cards or sheets can be kept in a case if so desired.

It has been found by actual experience, that the number of different symptoms will run up in the thousands, and thus there will be several thousand of the cards 10.

It has also been found that the known remedies for treating diseases, as used in the homeopathic profession are approximately 425 in number and thus the cards are divided into 425 spaces and numbered accordingly, but it is to be understood that as other medicines become known, other spaces or squares are made or added to the cards or sheets 10.

After a physician has found all of the symptoms of a patient, he can look on the leaves or sheets B and find the numbers of the cards or sheets 10 representing said symptoms and then select the cards and arrange the same in superposed relation as shown in Figure 2 of the drawings. Now, perforations of the cards which align indicate the remedies which can be used for all of the symptoms, and thus which is the medicine which would be selected, and if two or three perforations align, the medicine having the highest relative value for treating the symptoms would be selected. This selection of course, would go by the colors on the perforated squares or spaces.

For example, suppose a case with the following symptoms, selected from a great number in order to show the superior advantage of the colored sheet repertory A: Great constipation on account of hard faeces and inactivity of the rectum, inflammation of the urethra and prostate, bloody urine, with tenesmus of the bladder, retention of urine with painful miction by drops, pain before and during miction, with internal burning, aggravation after midnight and by cold wet air.

By looking for these symptoms in the leaves or sheets B they are found to correspond with numbers 491-492-493-541-542-546-582-584-590-592-594-865-130

985—1975 and 2028, and the corresponding sheets are selected and superposed.

This superposition gives two remedies, as is indicated in Figure 2 of the drawings, represented by numbers 113, and 336, which respectively designate china and pulsatilla. In order to make a choice between these two remedies, the colors in the sheets are examined, and it will be found that china is marked two times in red, second class remedies, ten times in blue, third class remedies, and three times without color, fourth class remedies, while pulsatilla is marked five times in black, first class remedies, seven times in red, two times in blue, and one time without color. In consequence, pulsatilla would be selected. While the perforations or openings in the symptoms sheets afford a convenient means of determining the medicines which would be used for a diagnosis of several symptoms, yet other like expedients may be employed in lieu of openings, such as the provision of transparent or translucent lenses or the like.

25 From the foregoing description, it can be seen that a novel means has been provided for facilitating homeopathic physicians in their selection of medicines for treating different diseases.

30 Changes in details may be made without departing from the spirit or scope of this invention; but,

I claim:

1. Means for facilitating the selection of medicines in the treating of diseases consisting of a plurality of sheets, each representing a different symptom, of a disease, each sheet having a plurality of different characters thereon representing all of the known medicines, means indicating the medicines which are considered remedies for the symptoms marked on the sheets, means for indicating the relative value of the medicines for treating the said symptoms and a key sheet having characters on the first mentioned sheets printed thereon with the names of the medicines represented thereby printed adjacent thereto.

2. Means for facilitating the selection of medicines in the treating of diseases consisting of a plurality of consecutively numbered sheets, each representing a different symptom of a disease, each sheet having a plurality of different characters thereon representing different medicines, certain characters on each sheet designating the medicines which are considered remedies for the symptoms marked, and a key sheet bearing the numbers of said first mentioned sheets with the name of the symptoms printed adjacent to the same.

3. Means for facilitating the selection of medicines in the treating of diseases consisting of a plurality of sheets each repre-

senting a different symptom of a disease, 65 each sheet being consecutively numbered, a key sheet having the names of all of the symptoms written thereon and the numbers indicating the sheets printed adjacent thereto, each of the first mentioned sheets having 70 a plurality of different characters thereon representing different medicines, means designating those medicines of the first mentioned sheets which are considered to be 75 remedies for the symptoms written on the first mentioned sheets, and a second key sheet having the characters representing the different medicines printed thereon with the names of the medicines represented by said 80 characters printed adjacent to said characters.

4. A homeopathic repertory for facilitating the selection of medicines for the treating of different diseases comprising a set 85 of sheets each representing a different symptom of a disease, each sheet being divided into a plurality of like spaces, the spaces of each sheet being consecutively numbered, each number representing a different medicine, certain spaces of each 90 sheet being perforated to indicate the medicines which are considered remedies for the symptoms marked on the sheets, the perforated spaces being colored in different manner to indicate the relative value of the medicines for treating the symptoms marked on the sheets, and a key sheet having numbers printed thereon corresponding to the numbers in the spaces on the sheets 95 and with the names of the medicines represented by said numbers printed adjacent to said numbers.

5. A homeopathic repertory for facilitating the selection of medicines for the treating of diseases comprising a set of sheets 105 each representing a different symptom of a disease, the sheets being consecutively numbered, a key sheet bearing all of the names of the symptoms indicated on the sheets 110 with the numbers of the sheets printed adjacent thereto, each sheet being divided into a plurality of equal and like spaces, the spaces being consecutively numbered, each number representing a different medicine, a second key sheet having the numbers of the spaces printed thereon in consecutive order, and the names of the medicine represented by said numbers printed adjacent thereto, certain of the spaces of each sheet being 115 perforated to indicate the medicines which are considered remedies for the symptom marked on the sheet, and means designating the perforated spaces in different ways to indicate the relative value of the medicines for treating the said symptoms.

6. Means for selecting medicines for treatment of disease comprising a plurality of sheets each representing a different symp-

tom of disease, each sheet having means thereon including openings for indicating remedies for the particular treatment of the symptom represented on the sheet, the openings designating like remedies of the different sheets being positioned in similar areas of the different sheets, so that when a plurality of sheets representing the symptoms of a patient's ailment are placed in super-
posed relation, a person may determine the remedy for the ailment by selecting that remedy or remedies which are designated

by the openings of the sheets which are in aligning relation on all of the sheets.

7. As an article of manufacture a device ¹⁵ for selecting remedies for treatment of disease comprising a sheet having a disease symptom designated thereon, said sheet having openings therein which designate particular remedies for the treatment of the ²⁰ symptom, and means adjacent said openings for determining the relative value of said remedies for the treatment of that symptom.
